METALWORKING MACHINE

John Huber, Los Angeles, Calif., assignor to
 United Concrete Pipe Corporation, Los Angeles,
 Calif.

Application March 24, 1936, Serial No. 70,625

7 Claims. (Cl. 90—38)

This invention relates to planers. The general object of the invention is to provide an improved method and apparatus for planing the edges of metal plates or sheets.

5 In the art of plate welding it is essential that the edges of the abutting sheets be bevelled or recessed so that the arc will pass through the joint and deposit sufficient metal to effect a tight seal. In the practice heretofore employed it has

10 been customary to endeavor to hold the edge of the sheet in a flat position and to run the planer over the edge of the sheet so held. In practice, however, it has been heretofore found impossible to bring the edge of the sheet into a sufficiently

15 straight line so that a uniform cut can be secured throughout the entire length of the sheet.

My invention seeks to overcome these difficulties by providing an apparatus wherein the sheet or plate is suitably supported and wherein my improved planer is provided with a pair of rollers which engage one on each side of the plate edge and adjacent to a cutting tool so that the relation of the edge of the plate to the tool does not vary during the cutting operation so that a cut of uniform cross section will be secured.

20 A more specific object of the invention is to provide a planer including a fixed roller on a work engaging member and a movable member with a cutting tool associated with the latter member so that a cut of uniform cross section will be secured.

25 Another object of my invention is to provide a novel method of planing the edge of a metal plate.

30 Other objects and the advantages of the invention will be apparent from the following description taken in connection with the accompanying drawings, wherein:

Fig. 1 is a front face view of my improved planer device;

40 Fig. 2 is an enlarged, top plan view of the carriage portion of the planer device with portions thereof broken away;

Fig. 3 is a front face view of Fig. 2;

Fig. 4 is a section taken on line 4—4 of Fig. 5 with portions thereof broken away;

Fig. 5 is an enlarged section taken on line 5—5 of Fig. 1;

Fig. 6 is a section taken on line 6—6 of Fig. 3;

Fig. 7 is a longitudinal section through one of 50 the propelling screw bearings; and

Fig. 8 is an end view of a cylinder made from a flat metal plate the sides of which have been bevelled by my improved planer device and shows the joining sides magnified.

55 Referring to the drawings by reference charac-

ters I have shown my invention as embodied in a planer which is indicated generally at 10.

As shown the planer includes a suitable base 11 which may be supported on concrete or masonry and arranged upon this base 11 I show a pair of 5 H-beams 12 which are spaced apart and which are connected by transverse bars 13 the ends of which are welded to the webs of the H-beams 12.

On the under surface of the outer edges of the top flange I provide runners 14 which are secured to the flanges as by welding and above the flanges I provide other runners 15 similarly secured in place. These runners after being welded in position are finished to size.

The carriage of my planer is indicated at 16 15 and is provided with a top surface 17 and with downwardly directed side portions 18 the lower surface of which extend to the lower surface of the lower runners 14. An attaching plate 19 is secured to the lower surfaces of the sides as by bolts 20. The distance between the inner faces of the sides 18 is greater than the distance between the outer faces of the runners 14 and 15 and each space thus provided receives a gib 21. The gibs are engaged by set screws 22 and are normally urged inwardly against the outer face of the runners. The ends of the set screws are provided with recesses in which pins 23 are mounted. These pins engage a recess in the gibs 21 to prevent movement of the gibs relative to the sides 18. 25

The front of the carriage includes a raised portion 30 at each side and on each raised portion a base plate 31 is secured by bolts 32 and on each base plate an upwardly inclined frame member 33 is welded. The tops of the frame members 33 are connected by a block 34. A metal plate 35 is welded to the inner surface of the frame members 33 and to the lower surface of the block 34. The plate 35 has guides 36 secured thereto and these guides support a bearing block 37 which has a recess 38 in its upper surface to receive a screw 39 which rotates therein. The screw includes a head 40 and a threaded shank which is threaded into the block 34 and the construction is such that when the screw 39 is rotated by the grip 41 the bearing block 36 will be moved vertically.

The rear of the carriage has a raised portion as at 50 at each side and on each raised portion is a base 51 which is secured to the carriage by bolts 52. On the base 51 vertical posts 53 are welded and these posts are connected at their tops by a cross bar 54. Plates 53' serve to brace the posts 53. Welded to the cross bar are a pair of posts 55 each of which is provided with a semi-

cylindrical recess 56 at its upper face and a shaft 57 is mounted in the recess 56 and is rotatably held in place by a block 58 which has a semi-cylindrical recess 58' in its lower face. The block 58 is held in place by bolts 59 which pass therethrough into the posts 55. The shaft 57 includes a central portion 60 of enlarged diameter which is connected to a collar 61 and this collar receives a pivot bar 62 which is held in the collar by means 10 of a set screw 63.

The pivot bar 62 is thus mounted so that it can shift about the axis of the shaft 57 and the end portion of the pivot bar remote from the shaft 57 passes through an aperture 64 in the bearing block 37 and the construction is such that when the screw 39 is rotated the pivot bar 62 will swing vertically about the axis of the shaft 57. The front end of the bar 62 is provided with a key 65 which engages in a keyway 66 in the bearing block 36 to prevent rotation of the pivot bar 62.

Mounted upon the top 17 of the carriage is a guide member 70 which is recessed at its edges to provide a dovetail 71 which fits a correspondingly dovetailed tool holder 72, the upper surface 25 of which slidably engages the bottom of a plate 73 which is held in engagement with the lower surface of the plate 35 by screws 74.

The tool holder 72 is provided with a plurality of tool receiving apertures 75. The apertures 75 are shown as three in number although it will be understood that this number may be varied to suit the particular requirements in each case. Cutting tools 76 are held in the apertures 75 by means of set screws 77. I prefer to use one or 35 two cutting tools at a time.

The tool holder 72 is connected by screws 80 with a threaded block 81 in which a screw 82 rotates. The end portion of the screw remote from the block 81 includes a cylindrical portion 40 which is supported in an aperture 83 on the carriage. The screw 82 is provided with a hand wheel 84 by means of which it may be rotated to advance the tool 76 towards and from the work.

In order to move the carriage 16 along the 45 work I provide a screw 90. This screw rests in a semi-cylindrical recess 91 in a bearing block 92 which is supported on the bars 13. These bars are distributed at intervals along the beams 12. The upper half of the screw 90 engages in a 50 recess 93 in the carriage. This recess is of greater radius than the exterior radius of the screw 90 and holds a semi-cylindrical Babbitt nut 94 which is cast in place and the construction is such that when the screw 90 is rotated the carriage 16 will be moved. Adjacent opposite ends of frame 11 the screw 90 is shown as supported by anti-friction bearings 95 which are mounted on cross members 96 which are secured to the H-beams 12 by welding them thereto.

60 At one end the screw 90 is connected through a flexible coupling member 97 to the armature shaft 98 of a gear reduction electric motor 99. (See Figs. 1 and 7.)

The front end of the carriage 16 supports an 65 axle 100 which is fitted in an aperture therein and which is held in place by a pin 101. Mounted on the axle is a collar 102 and a roller 103, the latter of which has a periphery which is preferably rounded. The outer end of the axle 100 is 70 of reduced diameter and receives a washer 104 and a nut 105.

The end of the pivot bar 62 includes an axle portion 106 at its free end. This axle supports a collar 107, roller 108, washer 109, and nut 110.

75 Like the roller 103 the roller 108 has a rounded

periphery and the two rollers are in vertical alignment.

In the drawings I have shown the rollers as engaging the top and bottom of a plate 111 which is shown as having a portion of the side 112 being 5 removed by the bevel end of the cutting tool 106 to form a beveled portion 113 on the side of the plate. After opposite sides of the plate 111 are beveled the plate is formed into a cylinder with the beveled sides together as shown in Fig. 8. 10 After the plate has been formed into a cylinder the two sides 112 of the plate are welded together in the space between the beveled portions 113.

I preferably provide the rear of the guide member 70 with an aperture 121 and the carriage 16 with a similar aperture 122 and in these apertures I seat a pivot pin 123 which has a flange 124 at its upper end so that the guide member 70 may shift about the axis of the pivot pin 123. 20 The pivot pin 123 has a threaded aperture 125 therein in which a bolt 126 is mounted to hold the pivot pin in position.

Mounted on the top of the carriage I secure a pair of supports 127 each of which has a hole 25 128 therein through which a spring 129 passes. One end of each spring 129 is mounted within a housing 130 which is held in place by screws 131, while in the housing a reaction member 132 is adjustably held in place by a screw 133. The 30 other end of the springs 129 each engage a plate 134 on the guide member 70. By adjusting the screws 133 the tension of the springs may be adjusted.

From the foregoing description it will be apparent that I have provided a novel planer device which is simple in construction and highly efficient in use.

Having thus described my invention I claim:

1. In a planer, a movable carriage, a support 40 adapted to engage a work plate and adjacent the movable carriage, means on said carriage and adapted to engage the under side of one edge of a plate on the support, an elongated bar on said carriage, a second plate engaging means on the 45 end of said bar, and disposed to engage the top of a plate on the support, pivot means on the end of said bar remote from said plate engaging means for supporting said bar, a cutter member mounted on said carriage adjacent one of said 50 means, and means to move said carriage.

2. In a planer, a movable carriage, a support adapted to engage a work plate and adjacent the movable carriage, a roller on said carriage and adapted to engage the under side of one edge 55 of a plate on the support, an elongated bar on said carriage, a second roller on one end of said bar, said rollers being in alignment and disposed to engage a plate on the support between them, pivot means on the other of said bar remote from 60 said roller for supporting said bar, a cutter member mounted on said carriage adjacent one of said rollers, and means to move said carriage.

3. In a planer, a support for a plate, a base, uprights on said base, runners mounted on said 65 uprights, a carriage slidable on said runners, said carriage having a threaded portion thereon, a threaded rod engaging said threaded portion to move said carriage, a roller on said carriage, a cutter mounted adjacent to said roller, a second 70 roller mounted on said carriage and movable towards and from said first roller, said second roller being in alignment with said first roller.

4. In a planer, a support adapted to engage a plate, a movable carriage, a roller on said car- 75

riage and adapted to engage the under side of one edge of a plate on said support, said roller being mounted on a fixed axis, an elongated bar on said carriage, a second roller on the end of 5 said bar, said rollers being in alignment to receive a plate between them, pivot means on the end of said bar remote from said roller for supporting said bar, a cutter member mounted on said carriage adjacent said second roller, means 10 to adjust said cutter member laterally and forwardly and means to move said carriage.

5. In a planer, a base, a carriage slidably mounted on said base, means to move said carriage, a tool holder, means to mount the tool 15 holder on the carriage for movement about a vertical axis, a tool in said tool holder, resilient means on said carriage intermediate the length of said tool holder and on each side of the tool holder to hold said tool holder in adjusted position, a work engaging member on said carriage adjacent the tool holder and a second work engaging member on the carriage adjacent the tool holder and the first work engaging member.

6. In a planer, a base, a carriage slidably 20 mounted on said base, means to move said carriage, a tool holder, means to mount the tool

holder on the carriage for movement about a vertical axis, a tool in said tool holder, resilient means engaging each side of the tool holder to hold said tool holder in adjusted position, a work 5 engaging member on said carriage adjacent the tool holder, a second work engaging member on the carriage adjacent the tool holder and the first work engaging member, and means to move the working members towards and from each other.

7. In a planer, a base, a carriage slidably mounted on said base, means to move said carriage, a tool holder, means to mount the tool holder on the carriage for movement about a vertical axis, a tool in said tool holder, resilient 15 means intermediate the length of said tool holder and on each side of the tool holder to hold said tool holder in adjusted position, means to independently adjust the resilient means, a work engaging member on said carriage adjacent the tool holder, a second work engaging member on the carriage adjacent the tool holder and the first work engaging member and means to move the working member towards and from each other.
